MILK CAN CARRIER

David M. Mestmaker, Odessa, Mo.

Application November 19, 1951, Serial No. 17,467

Term of patent 14 years

(Cl. D14—3)

To all whom it may concern:

Be it known that I, David M. Mestmaker, a citizen of the United States, residing at Odessa, in the county of Lafayette and State of Missouri, have invented a new, original, and ornamental Design for a Milk Can Carrier, of which the following is a specification, reference being had to the accompanying drawing forming a part thereof, wherein:

Fig. 1 is a side elevational view of a milk can carrier, showing my new design.

Fig. 2 is a front elevational view thereof; and Fig. 3 is a top plan view thereof.

I claim:

The ornamental design for a milk can carrier, as shown.

DAVID M. MESTMAKER.
